UNITED STATES PATENT OFFICE.

HEINZ MAY, OF HANOVER, GERMANY.

RESTRETCHABLE TENNIS RACKET.

Application filed April 26, 1926, Serial No. 104,701, and in Germany August 31, 1925.

This invention relates to a re-stretchable tennis-racket and has for its object to transmit the tensile stress, exerted onto certain strings of the net by the striking of the ball or by other reasons, upon adjacent and other strings and upon the whole net. By special conducting of the strings the frame itself is made elastic, the tensile stress is transmitted upon said frame and the warping of the frame is prevented. This transmission of the tensile stress and the distribution of the same over the whole net has the effect that the strings in the central portion of the net, which are most struck are spared and that breaking of the strings or slackening of the tension of the net are prevented. The means used, for the purpose aimed at, prevent further rupture of the strings at the edges of the holes through which the strings are passed through the frame and these means make it possible to re-stretch the strings if they get slack.

Several embodiments of the invention are shown, by way of example, in the accompanying drawings, in which

Figs. 1, 2, 3 and 4 show each in front elevation a tennis racket stringed in a different manner.

Fig. 5 is a diagram illustrating the manner in which the stringing of the racket shown in Fig. 4 is carried out.

Fig. 6 is a part-section through the plane of the racket frame on line VI—VI of Fig. 9.

Fig. 7 is a cross section of Fig. 6.

Fig. 8 is a part section through the plane of the frame showing how the ends of the strings are fixed.

Fig. 9 shows in plan view the outer side of the racket frame.

Fig. 10 is a part section through the plane of the net similar to Fig. 6 but showing another form of stringing.

Fig. 11 is a cross section of Fig. 10.

Fig. 12 is a section on line XII—XII of Fig. 10.

Fig. 13 shows in plan view a portion of the racket frame and illustrates the method and means for re-stretching the strings.

Fig. 14 is a cross section of Fig. 13.

Fig. 15 shows in plan view a portion of the racket frame and illustrates another method and means for re-stretching in two different positions.

Fig. 16 shows in plan view a portion of the racket frame and illustrates in the left

half a third and in the right half a fourth method and means for re-stretching the strings.

The fundamental idea of the invention consists in providing for the strings, at the points where they enter into the holes in the frame or at a slight distance from the inner surface of the frame, movable bearings which, by sliding to and fro on the inner surface of the frame, effect an equalization of tension between the two strings held by one bearing, said bearings leading the strings in such a manner into the frame-holes that friction of the strings on the edges of the frame holes is avoided. As bearings serve rings *d*, *d'* situated in front of the frame holes and designed to receive each one pair of strings or the loops *f* of a cord *c* extending, close to the inner surface of the ratchet frame, around the net. Both these means may be used together.

Figs. 1 and 2 show in which manner the frame of a tennis racket can be stringed. The stringing shown in Fig. 2 will be preferably used, as at the playing the ball strikes, in most cases, not at right angles to the net whereby the stress upon the strings, if diagonal stringing is used, is more favorable and consequently less strain is caused than if the bearings for the strings are in the wooden frame. Owing to the continuous cord *c*, which in tightly tied loops *f* is tied around the strings *b*, and by the rings *d*, the tension of the strings is transmitted upon other strings not directly struck by the ball.

The arrangement of the rings is shown on larger scale in Figs. 6 and 7. By one ring two adjacent strings *b* are held together, so that the direction of the pull of a string put under stress, owing to the pushing of the ring in lateral direction caused hereby, is transmitted also upon the adjacent string which is pulled by the ring. The rings form therefore slideable bearings for the strings and they rest upon the inner surface of the racket frame *a* in front of the holes *e* or *i*. The strings pass through the holes *i* in the wooden frame *a*. The holes are enlarged in the plane of the net towards both sides so that the strings *b* are free to move in the holes at *e* towards both sides without rubbing on the edges of the holes. The holes *i* are displaced and arranged in a zig-zag shaped groove *g* in the outer surface of the frame, as shown in Fig. 9, and they merge

- on the inner surface of the frame into the plane of the net. At a short distance from the inner surface of the frame, preferably at the second point of intersection of the 5 strings, a continuous cord *c* is conducted around the net which cord is tied around intersections of the strings. The knots of the cord *c* transmit the pulling tension of the strings in a similar manner as the rings. 10 The cord *c* serves further to effect an equalization of the tension over the whole net, so that, if one or two strings are struck by a ball, the pulling effect is not only transmitted upon the adjacent strings but in a 15 lesser measure also upon all other strings.
- In the stringing shown in Fig. 2 two separate cords *c* are used at the transverse sides of the frame in order to equalize the tension especially in the longitudinal direction of 20 the frame. A string could not be used instead of this cord, as a string, owing to its hardness would embrace the strings *b* in one line and cut at first, owing to tension which occurs, into the strings and damage them. 25 An ordinary cord of the same thickness as the strings is best suited, the cord being tied and knitted around the strings, and, if the net is finished, impregnated with oil and varnish. The bearings for the strings formed 30 by the knots *f* of the cord *c* embrace the strings band-like and the desired resistance and solidity is given to the same by the subsequent treatment with oil and varnish. The effect is obtained that the connecting cord 35 in consideration of its function, e. g. the interception of slighter tensions, is of the same durability as the strings.
- In the form of stringing shown in Fig. 3 the rings *d* are suppressed and a cord *c'* is 40 substituted for the same, the tightly tied loops *f'* of which are not tied around the points of intersection of the strings but enclose the strings at the points where they come out of the holes *e* of the frame. The 45 loops *f'* therefore take over the function of the rings *d* and the cord *c'* fulfills at the same time the function of the cord *c* used in the forms of construction shown in Figs. 1, 2 and 6.
- 50 In the form of construction, as shown in Fig. 4, no connecting cord is used and the effects of the pull are distributed with the aid of a certain scheme for inserting the strings, by which the frame itself is rendered elastic in inward direction and the tensile stresses are distributed so that the elasticity of the frame is thereby produced. In this stringing the rings *d* are arranged in four groups, one larger group, of for instance 55 15 rings at each long side *m*, *m* of the racket-frame, and one smaller group, of for instance 10 rings, at each short side *n*, *n* of the racket-frame *a'*. To a selected number of 60 rings on the short sides correspond a determined number of rings on the long sides, 65 so that the relation of the longitudinal axis of the frame to the transverse axis of the same and the plane-shape of the frame are determined or influenced by the number of rings. Between the long sides *m*, *m* and the short sides *n*, *n* of the frame are the portions *g*, *g'* and *o*, *o'* into each of which 5 strings are strung without rings, so that these strings are stationary. The net of the 70 racket consists essentially of two string lengths *p* and *q* extending through the entire net and being clamped alternately so that they intersect one another, in order to obtain a symmetrical figure with regard to the main axis of the racket. The two long 75 strings *p* and *q* begin at the points *r* and they end, after the net has been finished, at *r* and *s'*. The rings *d* are strung in together 80 with the insertion of the strings.
- If one string-portion of the net, between 85 every two holes of the frame, is called a stretch, each of the two long strings form 30 stretches if the net is finished, or together 60 stretches. If one follows the string- 90 stretches coming out of the holes, 1, 2, 3, 4, 5 or 6, 7, 8, 9, 10 of the frame-portions *g* and *o*, one will see from the diagram of plaiting shown in Fig. 5, that each string *p* and *q* forms from the frame-portion *g* to *g'* or *o* to *o'* each 5 by 6 stretches, of which always the 95 first stretch begins at one of the fixed bearing points 1 . . . 10, and ends in one of the fixed bearing points 1', 2' . . . 10', so that by these 60 stretches the entire net is formed. The net can be imagined as formed of portions of strings beginning at the points 1 to 10 and ending at the points 1' to 10', each 100 string-portion between the starting- and end-point forming six stretches of the net. Only the starting- and end-points represent 105 stationary bearings, as at these points no rings are used and the strings are not yieldably mounted in these frame holes which form the starting- and end-points. Through 110 all the other frame holes the strings are passed through the intermediary of bearing-rings *d* or *d'* (Fig. 10) so that said strings are yieldable. At the points 1 to 10 and 1' to 10', or in the frame-portions *g*, *o* and *g'*, *o'* no transmission of the pulling effect from 115 one upon the other stretch of strings takes place, whilst at all other passage-holes of the portions *m*, *m* and *n*, *n* of the frame rings *d* or *d'* are arranged, according to Figs. 6 or 10, 120 and a transmission of the pulling-effect from one upon all other points (movable bearings) takes place. At the frame-portions *m*, *m* and *n*, *n* act consequently 30 or 20 string- 125 stretches together at the same time, and these pulling-effects are supported towards the frame-portions *g*, *o* and *g'*, *o'* which form the counterbearings. At the points *g*, *g'*, *o*, *o'* the tensile force acts in the direction of the string stretches and on the portions *m*, *m* or *n*, *n* of the frame acts, in consequence of 130

the equalization by the rings, one resulting force for each portion at right angles to the frame towards the centre of the net. The latter forces effect a vibration of the frame portions m, m or n, n with regard to one another.

By this stringing the rigid wooden frame is made elastic in such a manner that the principal vibrations in the central portion of the net are damped in first instance by the stringing which gets denser towards the frame. By the fact that the long sides of the frame vibrate with the strings the vibrations are propagated until they arrive at the four rigid portions g, g', o, o' of the frame. The long sides of the frame yield under the vibrations which occur in the plane of the net, so that the net plane is elastic in the longitudinal direction, being in this direction elastically held by the short sides of the frame. An equalization of the tension takes place directly after the strings have been put under stress.

The advantages resulting from this stringing consist in that breaking of the strings or warping of the frame owing to the influences of temperature and moistness, and excessive slackening of the strings due to the playing or storing are avoided. In the stringings of known type, which are mostly rectangular, the points g and g' and o and o' cause mainly warping of the frame as two string stretches act with different force in angular direction in one hole without forming a component force which might counteract the yielding of the frame. Herefrom results that a racket according to the invention does not require a frame-press, which might even have a prejudicial effect on the stringing as it prevents the equalization of the tensions in the frame and in the strings or temporarily brakes the movement in the frame caused by influences of temperature so that, after the frame press has been removed, breaking of the strings could be caused by a one-sided sudden warping of the frame.

In the form of stringing shown in Fig. 4 the bearing rings d' are preferably of a special shape as shown in Figs. 10 and 11. They are enlarged at one end and have at the other end a circular flange, their enlarged front end holding two strings b and b' so that they lead the tension of the strings gradually over to the reinforced foot and thence to the frame.

In Figs. 8 and 9 the fixation of the string ends is illustrated. In the stringings of tennis rackets commonly used up to the present strings had to be used which are as long as possible as it was difficult to fix the ends of the strings well. Two strings were used for the long and cross stringing. If repairs had to be done by replacing certain string-stretches a special difficulty

arose, and besides by making knots in the strings the ends of the same were held in the frame by means of wooden wedges.

In the stringing, according to the invention, the fixation of the ends is carried out in the following manner. In the outer surface of the frame, between every two holes $i, i', i^2, \dots$ an incision h intersecting the zig-zag groove b at right angles is arranged. The end of the string b' (Fig. 8) is passed through the hole i in the direction of the arrow, then over the frame-bearing k through the second hole i' and under the bearing k' inside the frame, through the hole i^2 to the outer side. The projecting end of the string is then passed through the incision h at the left of the hole i^2 and pulled in upward and lateral direction. The string b' gets at this occasion between the stretched string b^2 and the bearing k' and slips underneath the rounded portion l of the bearing k' . The string end b' is then passed through the incision h' at the right of hole i^2 and stretched. By the alternate use of the incisions h and h' and by the passing of the string end b' over the rounded portions l and l' two stretched strings b^2, b^3 are wound around in spiral-shape.

The right side of Figs. 8 and 9 shows the string end b' , after the incision h has been used, and shows further how the string end is pulled through the incision h' . The left side of these figures shows another string-end b^4 . On this string end the tying up through the two incisions at the left and right of the hole i^4 has been caused already and the end b^4 is clamped between the string b and the bearing k' .

The tying can be further extended in a similar manner and the incision of bearing k can eventually be utilized also for the tying. It is however advisable to leave the string end clamped finally between a bearing k and the string b , as this is shown at b^4 . By this manner of fixation it is possible to fix also short strings securely and in a not conspicuous manner, as is necessary for repairs. At the same time two strings (b^2 and b^3) are tightly tied around by the tying in one hole (i^2, i^4) so that the string (b^2 or b^3) which is put under stress in the racket-net transmits its tension upon two strings in the stationary bearing k and the dangerous cross section of the string, which is situated where the string rubs on the wood, is as good as suppressed.

A further inconvenience, which every racket-net possesses, is the slackening of the stretched strings, either owing to the use at playing or to the influences of temperature.

Figs. 13, 14, 15 and 16 show methods and means for re-stretching the strings. In the form of construction shown in Figs. 13 and 14 the rings I are pulled away from the frame a , on the strings which they enclose,

by a cord *t*, which is guided between the two strings coming from the hole *e* passes around the outer side of ring *d*, is pulled towards the next following intersection *u* of the strings and stretched. The rings *d* are thereby all pulled away more or less from the frame. By the shortening of the string stretches caused hereby re-stretching of the strings is effected.

16. Another possibility of regulating the tension in the racket-net within certain limits is the arrangement of the incisions *h* as shown in Figs. 8 and 9. Pieces of thick cord are pulled through the incisions and brought, at the right and left of the incision, upon the bearing *k* of the frame so that the cords rest between the string and the bearing *k*. Shortening of the string for up to double the depth of the incision can thus be obtained.

Fig. 15 shows an automatic regulation of the tension of the racket net.

Instead of one, two rings *d*, *d* are stringed into the net at every hole in the frame, a spiral spring *v* being inserted between said two rings. The left side of Fig. 15 shows a part elevation of the frame and of the racket net at normal state, for instance immediately after the net has been finished. The net shown at the right side of the figure has suffered through any influences and lost tension. The spring *v* has expanded in accordance with the slackening of the tension and has pushed the rings *d*, *d* away from each other whereby these rings have re-established the tension of the strings after the same principle as in Fig. 13.

By means of the rings *d'* which are of special shape the re-stretching can be effected by means of cords, as shown in Fig. 16. The cord *w* is strongly jammed, in the form of construction shown in the left half of Fig. 16, between the inner side of the frame and the collar of the ring *d'* which bears against the frame, and wound as often as possible around the strings *b*, *b'* guided in the ring, the turns of the cord touching one another. The ring is thus pushed away from the frame, whereby the strings are re-stretched as in Fig. 13. The cord extends from one ring to the other.

In the form of re-stretching shown at the right half of Fig. 16 the cord *w'* is wound only once around the strings *b*, *b'* the rings being further pushed away from the frame by a second cord *x* which extends, between the attached portion of the cord *w'*, from one ring to the other, and guided around the next following point of intersection of the strings at *y* and pulled tight. The action of this cord *w* is similar as that of the cord *t* in Fig. 13.

I claim:

1. A re-stretchable tennis racket, comprising in combination with the frame and with

the net, movable bearings in the shape of rings each ring enclosing one pair of strings at the points where the strings pass through the frame said strings serving to transmit the tension from one string to the adjacent string, to other strings of the racket-net and to certain portions of the frame. 70

2. A re-stretchable tennis-racket, comprising in combination with the frame and with the net, movable bearings in the shape of rings each ring enclosing one pair of strings at the points where the strings pass through the frame said strings serving to transmit the tension from one string to the adjacent string, to other strings of the racket-net and 75 to certain portions of the frame, and a cord extending at a short distance from the inner side of the frame and from said rings around the net said cord embracing in loop- or knot-shape the strings at the points of intersection in order to distribute the pulling action of the strings over the entire net. 80

3. A re-stretchable tennis racket, comprising in combination with the frame and with the net, movable bearings in the shape of rings each ring enclosing one pair of strings at the points where the strings pass through the frame said strings serving to transmit the tension from one string to the adjacent string, to other strings of the racket-net and 90 to certain portions of the frame, and pieces of a cord extending at a short distance from the inner side of the frame and from said rings around portions of the net said pieces of cord embracing in loop- or knot-shape the 95 strings at the points of intersection in order to distribute the pulling action of the strings over portions of the net. 100

4. A re-stretchable tennis-racket, comprising in combination with the frame and with the net, four groups of rings arranged on the two long sides and on the two cross sides of said frame and enclosing each ring two strings at the points where said strings enter into the frame, the strings between the frame 110 portions on which said ring groups are arranged being attached directly to the frame so that the tension of the net is transmitted upon the four main portions of the frame to which thus a certain elasticity is given. 115

5. In a re-stretchable tennis racket as claimed in claim 4 the rings having an enlarged front end and a collar at the rear end so that they take up the tension gradually and guide it over onto the reinforced 120 rear end.

6. In a re-stretchable tennis racket as claimed in claim 1 comprising in combination with the ring and the strings a cord wound in zig-zag shape around the rings 125 and the first points of intersection of the strings in order to pull the rings away from the frame.

7. In a re-stretchable tennis racket as claimed in claim 1 comprising in combina- 130

tion with the frame, the strings and the rings, cords clamped between the inner side of said frame and said rings and wound around these portions of the said strings in order to pull the rings away from the frame for restretching the net.

8. In a re-stretchable tennis racket as claimed in claim 1 comprising in combination with the frame the strings and the 10 rings, a stretching cord wound around each string between the inner side of the frame and the rings, a second cord stretched in zig-zag shape between the first point of intersection of two strings and the connect-

ing portion of said stretching cord from 15 one ring to the other ring in order to push said rings away from said frame and for re-stretching the net.

9. A re-stretchable tennis racket, comprising in combination with the frame and with the net, two rings mounted on every two strings at the point where said strings enter into said frame, and a spiral spring between said two rings which pushes the rings away the one from the other and effects thus 25 the re-stretching of the net.

In testimony whereof I affix my signature.
HEINZ MAY.
